LEAD FOR PENCILS, COLOR PENCILS, COPYING PENCILS, OR THE LIKE AND PROCESS FOR MANUFACTURING THE SAME

Richard Zückert, Bohmisch-Budweis, Czechoslovakia, assignor to the firm "Koh-i-noor" tužkárna L. & C. Hardtmuth, Ces. Budejovice, Czechoslovakia

Application May 20, 1937, Serial No. 143,848
In Germany May 30, 1936

4 Claims. (Cl. 120—83)

This invention relates to a lead for black lead, colored and copying pencils and the like with artificially produced hollow space. These hollow spaces in the lead are, according to the invention, constructed as passages extending parallel to the axis of the lead, and preferably of such diameter that capillary effects are produced.

Such a lead may, for example be connected at its rear end with a container for a writing liquid such as ink which when the lead is being used for writing flows through the passages on to the paper and completes the line drawn with the pencil. In this manner the two fundamentally different proceedings of writing with a pencil and of writing with a nib are combined. A stroke drawn with a pencil alone cannot completely color the paper, as the lead particles adhere only on the projecting cellulose fibres of the paper and uncolored paper portions remain between them, this being particularly visible, if pencil strokes are copied by heliographic calking. Such uncolored paper islands are, however, attained by the writing liquid contained in the capillary passages of a lead according to the invention, so that it is thus possible to produce a drawing instrument of particularly great usefulness.

The lead with capillary passages presents further the possibility to produce a first-quality hectographic-ink stylus, which has not been possible up to the present, because the number of hectographic copies which can be made depends on the glycerine-percentage of the lead, which is however, very limited for technical reasons in the compact lead, these reasons being no longer valid for the lead having capillary passages according to the invention.

The manufacturing of a lead with artificial hollow spaces may be effected in various manners. A practical manner consists in admixing with the usual lead mass additions which contain an easily evaporating substance or a substance developing gases, to press the body of the lead to the desired shape, and to cause the development of the gas necessary for the formation of the hollow spaces by vacuum treatment, drying, heating or the like of the lead. An easily evaporating substance for instance naphthalene in powder state may be used.

The passages extending parallel to the axis of the lead may be produced in two different manners. The one manner consists in providing in the commonly used mass for leads parallelly extending bores and to fill these bores with a substance adapted to easily develop gas and of additions which render this substance plastic up

to the usual lead mass consistence, to press the thus produced body of lead mass to form a lead and to submit this lead to the treatment necessary for developing gas. According to the second manner a second body of suitable mass is prepared besides the usual body of lead mass, said second body consisting of the same substance as the above mentioned "insert", whereupon the two bodies of lead mass are shaped, in known manner, to strings of square or rectangular cross-section, and these strings mixed to a compound mass-body showing in cross-section the two masses mixed, chequered in squares, whereupon the compound mass-body is pressed to form a lead and this lead subsequently treated for gas development.

The advantages of the invention are present in some cases of application even then, if the dimensions of the hollow spaces become so great that the capillary effects are no longer predominant.

A favorable combination for the insert according to the invention in bodies of lead-mass is amongst others as follows:—

900 grs. naphthalene in the form of a very fine powder,

100 grs. calcium stearate in the form of finest powder,

25 grs. coloresin, (methyl cellulose) swelled in 400 grs. water.

Two embodiments of the invention are illustrated, by way of example, in the accompanying drawing, in which:—

Fig. 1 shows on an enlarged scale a cross section through a lead.

Fig. 2 is a longitudinal section on line II—II of Fig. 1.

Fig. 3 shows in longitudinal section the production of a lead in an ordinary lead press.

Fig. 4 is a cross section through the lead mass taken on line IV—IV of Fig. 3.

Fig. 5 shows on a slightly larger scale the pressed lead in cross section on line V—V of Fig. 3.

Fig. 6 shows in longitudinal section the modified manner of production of a lead in an ordinary lead press.

Fig. 7 is a cross section through the lead mass taken on line VII—VII of Fig. 6.

Fig. 3 shows on a slightly enlarged scale the pressed lead in cross-section on line VIII—VIII of Fig. 6.

The lead 1 in Figs. 1 and 2 has a central capillary passage 2 and eight capillary passages 3 uniformly distributed in a circle about the centre 55

passage. In producing this lead by the method illustrated in Figs. 3 to 5, an ordinary lead mass is shaped in the form of a cylinder 4 and provided with passages 5 which are filled with a second mass composed of a substance which easily gives off gas with suitable admixtures for rendering it plastic (Fig. 4). The cylinder 4 composed of two different masses is placed in a cylindrical press cylinder and subjected to pressure by a piston 7 which forces the mass through a mouthpiece 9 in compressed state in the form of a lead 8 (Fig. 3). Fig. 5 shows the cross section of the lead 8 whose passages or bores have become of capillary size owing to the reduction of the cross-sectional area, but are still filled with the mass which easily liberates gas. The compressed lead 8 is now subjected to a treatment for liberating gas whereby the finished lead with hollow capillary passages is produced.

20 Figs. 6 to 8 show a second manner for producing such a capillary lead. A number of strings 10 of square cross-section is produced from the ordinary lead composition. A number of strings 11 of exactly the same cross sectional shape is produced from a second composition capable of giving off gas. These strings 10 and 11 are then united to form a composite string as shown in Fig. 7, each string 11 being surrounded by strings 10 and consequently separated from the next string 11. This thick composite string is now inserted in a lead press 12 of square cross-section, in which it is forced through a mouthpiece to form a lead 14, as in the method illustrated in Figs. 3 to 6. If the mouthpiece is of circular cross-section a round lead is produced and the strings 11 of substance giving off gas, for example four in number, embedded in the composite string are deformed to more or less circular

cross section (see Fig. 8). The compressed lead is then subjected to a gas liberating treatment and is thereafter ready for use.

I claim:—

1. A lead for pencils, color-pencils, copying 5 pencils and the like, containing artificially produced continuous passages extending parallel to the axis of the lead.

2. A lead for pencils as specified in claim 1, in which the passages are in dimensions causing 10 capillary effects.

3. A process for the production of leads with continuous passages extending parallel to the axis of the lead, consisting in using a common lead mass having parallel longitudinal strands of 15 a second mass which consists of a granular substance easily developing gas and made plastic by convenient additions, in pressing the mixed mass to form the lead, and in finally treating this lead in a suitable manner for causing the gas 20 development.

4. A process for the production of leads with continuous passages extending parallel to the axis of the lead, consisting in producing, besides a body of commonly used lead mass, a second body 25 of a mixture consisting of a substance capable of developing gas and of additions adapted to render this substance plastic, in shaping these two kinds of bodies into strings of square cross-section, in uniting these strings to form a compound body in such a manner, that in the cross section of the compound body the strings of the developing substance lie on the places desired for the parallel passages, in compressing the compound body to the proportions of a lead, 30 and in submitting this lead to a treatment for developing gas.

RICHARD ZÜCKERT.
